UNITED STATES PATENT OFFICE.

CHARLES STEWART HASTINGS SNOW, OF CROYDON, ENGLAND, ASSIGNEE TO N. I. C. E. LIMITED, OF LONDON, ENGLAND.

TWO-STROKE-CYCLE INTERNAL-COMBUSTION ENGINE.

Application filed December 12, 1924, Serial No. 755,507, and in Great Britain June 4, 1924.

This invention relates to improvements in two-stroke cycle internal combustion engines and has for its object to increase their efficiency.

According to one feature of this invention, the pistons are made hollow throughout and the charge is passed through them. Thus, they constitute reservoirs or extra space for the charge which is thereby enabled to be transferred at a low pressure with consequent elimination of detonation on transfer. Further advantages of the aforementioned hollow pistons are that the temperature over the whole piston is reduced which enables a good piston fit to be secured, better vapourization of mixture to be obtained, reduces the liability of detonation due to piston head heat, and reduces condensation of the charge to a minimum.

According to another feature of this invention, there is provided, special valve mechanism to control the charge passing to the cylinders as hereinafter described. A third feature of this invention consists of a bypass or balancing passage to vary the transfer and also, if desired, to act as a throttle.

In order that this invention may be the more clearly understood and readily carried into effect, I will proceed to describe the same with reference to the accompanying drawings which illustrate embodiments of this invention, and wherein—

Figure 1 is a central vertical longitudinal section, partly in elevation, of a twin-cylinder two-stroke cycle internal combustion engine constructed in accordance with this invention.

Figure 2 is a central vertical section of valve mechanism for controlling the charge passing to the cylinders, constructed in accordance with this invention, and

Figures 3 and 4 are similar views of modified constructions of the said valve mechanism.

Like reference letters indicate like parts throughout the drawings.

Referring to Figure 1 of the drawings, the cylinders are each of two diameters and they consist of pump portions a , a^1 respectively and working portions b , b^1 respectively. The pistons are likewise each of two diameters, and they consist of pump portions c and c^1 fitted with rings c^2 and c^3 respectively, and working or head portions c^4 and c^5 fitted with rings c^6 and c^7 respec-

tively. The pistons are made hollow so as to constitute reservoirs and they are also of the deflector-head type. Each piston is formed with inner walls c^8 whereby a conduit is provided extending substantially from a port c^{10} at one side of the lower end of the piston, up to the top of the piston and down to a port c^{11} near the lower end of the other side of the piston. The pistons are, further, furnished with lubrication holes c^9 which communicate at their inner ends, with the crank-case, while their outer ends lead into grooves c^0 .

The fuel-induction ports, shown at a^2 and a^3 lead into the pump cylinders a and a^1 respectively.

d is the transfer passage, which is common to both of the cylinders.

e , e^1 are the exhaust ports of the cylinders b and b^1 respectively.

f shows the water jacket, f^1 being the inflow and f^2 the outflow. The spark-plugs are shown at g . The usual compression-release taps (not shown) are intended to be fitted in the apertures h .

The crank-case is made in two similar parts j and j^1 and they are cast from the same pattern, thereby simplifying and cheapening construction. The parts j and j^1 are secured to one another by bolts j^2 and to the cylinders by set-screws k . l is an oil well which is secured, by means of set-screws or the like, to the crank-case. It is provided with upstanding ribs l^1 furnished with holes l^2 ; the holes permit of circulation of the oil, while the ribs prevent its undue movement in the well. l^3 is an opening into which an oil-filter and breather pipe (not shown) are intended to be fitted, and l^4 , l^4 are apertures to receive drainage cocks.

Dealing now with the valve mechanism shown in Figures 2, 3 and 4, this is intended to be applied to the rear of the cylinders as they appear in Figure 1. It comprises a valve-chest m of which the middle portion is machined out to receive, in the construction shown in Figure 2, cylindrical valves n and n^1 which are connected together by a spindle n^2 , and in the construction shown in Figures 3 and 4, the liner m^1 of which the ends are bevelled to form valve seatings for the valves n^3 and n^4 . In Figure 3 the valve n^4 is formed integrally with the spindle n^5 which slides in a fixed guide n^6 , and the

valve n^3 is secured on the said spindle by means of a nut n^4 . In Figure 4 the valves are independent of one another and their spindles slide within the guide n^5 . The casing m is provided with inlets m^2 , m^3 , which are adapted to register with the fuel-inlet ports a^2 and a^3 (Figure 1) respectively. Into the ends of the casing m are screwed caps m^4 , m^5 through which are screwed adjustable stop-pins m^6 and m^7 (Figures 2 and 4) provided with lock-nuts as shown, these stop-pins being for the purpose of enabling the travel of the valves to be varied. Shock-absorbing buffers, such as n^8 (Figure 2) or springs, such as n^9 (Figure 4), may be employed to absorb the shock of the valves when working. The valve-chest is secured to the cylinders by means of lugs m^8 . Fuel is admitted to the space between the valves through an inlet in the side of the valve-chest remote from the cylinders, and the position that such inlet would occupy if the far side of the valve-chest were not removed (Figures 2, 3 and 4) is indicated by the chain-line circle m^9 .

Connecting the induction ports m^2 and m^3 together is a by-pass m^{10} wherein is fitted a rotatable plug m^{11} through which is formed a passage m^{12} . As shown in the drawings, the plug is in the closed position, but by rotating, and thereby opening, the plug the transfer can be varied to any desired degree. Thus, the by-pass constitutes a balancing passage and the control obtained by its use enables it to be used as a throttle. It will be clear that the by-pass can be made separate from the valve-chest and be connected direct to the pump cylinders.

Extra air can be admitted to the space between the valves through an opening m^{13} into which is fitted a tap m^{14} .

The operation of the engine is as follows:—

During the working stroke of piston c^4 fuel is induced into the pump cylinder a from whence it flows into the piston c^4 through the inlet and exit openings c^{10} and c^{11} therein. During the return stroke of this piston the charge is compressed in the pump cylinder a and in the piston c^4 until, the exhaust port c^1 of the cylinder b^1 having been uncovered by the piston c^4 , during the power stroke of this piston, the exit c^{11} of the piston c^4 is opened by the transfer passage d whereupon the compressed charge sweeps through the conduit of the piston formed by its outer and inner walls, and is transferred into the working cylinder b^2 . During the working stroke of the piston c^4 fuel is induced into the pump cylinder a^2 and into the piston c^5 , and when, during the return stroke of the piston c^5 , the exit port c^{11} therein reaches the transfer passage d (following the opening of the exhaust port c^1 by the piston c^4) the compressed charge

passes into the cylinder b , and so the operations are repeated.

It will be understood that, during the operation of the engine, the alternate suction and compression causes the valves in the valve-chest to reciprocate.

The internal capacity of the pump cylinders is preferably made in excess of that of the working cylinders whereby good scavenging is secured. Also, by reason of the excess volumes obtained by the hollow pistons the charges are transferred at a low pressure and the possibility of detonation on transfer is thereby eliminated.

Owing to the position and the short length of the transfer passage d the minimum of condensation results therein, and it is maintained at an even temperature.

Further, as the ports are arranged at right angles to the planes in which the connecting rods work, the wear on the cylinders and on the pistons is reduced to a minimum.

I claim:

1. The combination, in a two-stroke cycle internal combustion engine, of a plurality of duplex cylinders, duplex pistons working in said cylinders sweeps through the conduit of the piston formed by its outer and inner walls, and said pistons each being closed at its lower end and provided with a substantially U-shaped passage extending into the head of the piston and opening at its ends into the larger portion of the cylinder, mixture-inlet ports being formed in the walls of the larger cylinders and transfer ports in the walls of the smaller cylinders, the larger pistons serving to successively induce the mixture into the larger cylinders and into the hollow pistons and then to compress it therein, whereupon the compressed charges are successively transferred to the adjacent smaller cylinders.

2. In a two-stroke cycle internal combustion engine, a plurality of cylinders each comprising a pump portion provided with a mixture inlet port and a working portion of smaller diameter than the pump portion and provided also with a transfer port, pistons working in said cylinders, each of said pistons being provided with a substantially U-shaped passage permanently open at one end to the pump portion of the corresponding cylinder, extending up to the head of the piston and having its other end positioned to register with the transfer port when the piston is approximately at the top of its compression stroke.

3. In a two-stroke cycle internal combustion engine, a pair of pump cylinders, a pair of working cylinders in communication therewith and also connected together by a short transfer passage, pump pistons and working pistons working in the said cylinders respectively, mixture-inlets in the walls of the pump cylinders, the said pistons being re-

cessed at their lower ends to accommodate the connecting rods, and having their remaining portions made hollow in substantially U-form and completely cut off from the crank case, the said hollow portion opening out into oppositely disposed ports which permit the compressed mixture to be transferred through the piston and through the transfer passage into the adjacent working cylinder.

4. In a two-stroke cycle internal combustion engine, a pair of pump cylinders, a pair of working cylinders in communication therewith and also connected together by a short transfer passage, pump pistons and working pistons working in the said cylinders respectively, mixture inlets in the walls of the pump cylinders, the said pistons being recessed at their lower ends to accommodate the connecting rods and having their remaining portions made hollow in substantially U-form and completely cut off from the crank case, the said hollow portion opening out into oppositely disposed ports which permit the compressed mixture to be transferred through the pistons and through the transfer passage into the adjacent working cylinder, a valve chest connecting the said

mixture inlet ports together, and reciprocating valves in said valve chest to control the flow of mixture to the cylinders.

5. In a two-stroke cycle internal combustion engine, a pair of pump cylinders, a pair of working cylinders in communication therewith and also connected together by a short transfer passage, pump pistons and working pistons working in the said cylinders respectively, mixture inlets being formed in the walls of the pump cylinders, the said pistons being recessed at their lower ends to accommodate the connecting rods and having their remaining portions made hollow in substantially U-form and completely cut off from the crank case, the said hollow portion opening out into oppositely disposed ports which permit the compressed mixture to be transferred through the piston and through the transfer passage into the adjacent working cylinder, and a by-pass connecting the cylinders together whereby the transfer of the mixture can be controlled and whereby also the engine can be throttled.

In testimony whereof I have signed my name to this specification.

CHARLES S. H. SNOW.
